UNITED STATES PATENT OFFICE.

CHARLES S. McCLELLAND, OF PITTSBURGH, PENNSYLVANIA.

PUMP.

1,424,928.

Specification of Letters Patent. Patented Aug. 8, 1922.

Application filed May 14, 1921. Serial No. 466,818.

To all whom it may concern:

Be it known that I, CHARLES S. McCLELLAND, a citizen of the United States, residing at Pittsburgh, in the county of Allegheny and State of Pennsylvania, have invented certain new and useful Improvements in Pumps, of which the following is a specification.

My invention consists of an improvement 10 in air pumps for supplying compressed air to pneumatic tires, or for any other purpose.

The pump comprises a unitary generally cylindrical structure, comprising a plurality of relatively stationary and movable 15 concentrically arranged cylinders providing a middle high pressure chamber and outer surrounding medium and low pressure chambers respectively, constructed and adapted to operate in the manner more fully 20 hereinafter described.

The object in view is to provide, in a pump of the type involved, a series of compressing and storage chambers, within the concentric walls or shells of the associated 25 members, one of which is movable, whereby to utilize both the up-stroke and down stroke for continuous inflow of atmospheric air, and to effect successive cumulative compressions, with final delivery of high pressure air from the inner or middle chamber. 30

Referring to the drawings, illustrating one preferred embodiment of the invention,

Fig. 1 is a vertical sectional view of a pump constructed according to my invention, with the parts in an intermediate position;

Fig. 2 is a cross section on the line II—II of Fig. 1;

Fig. 3 is a cross section on the line III—40 III of Fig. 1;

Fig. 4 is a detail plan view of the annular spring tongue plate for resiliently extending the cup leather valve;

Fig. 5 is a sectional detail view showing 45 the spring tongue plate in position within the cup leather.

In the drawings, 2 is the base of the pump provided with the usual foot piece or standard and having an outlet or delivery 50 port 3 communicating with the central final compression or high pressure air chamber 4, and also with the usual delivery pipe or hose 5 of well known construction. Chamber 4 is provided by means of the central 55 tubular cylindrical shell 6 fixedly secured in the middle portion of base 2, extending

upwardly therefrom and terminating at the point shown. Cylinder 6 is provided with a stationary cup leather 7 secured thereon by outer and inner plates or rings 8, 9, and connecting screws or bolts 10, as will be readily understood.

Cup leather 7 is turned downwardly at its central portion to provide a packing engagement with the reciprocable central stem 65 or plunger rod 11 which is connected at its upper terminal with the usual cross handle 12. At its lower end, rod 11 is provided with a downwardly turned cup leather 13 secured by terminal stud 14, operable to seal 70 against the inner wall of cylinder 6 on downward movement, for compression, and to permit by-pass of air downwardly into chamber 4 upon upward movement.

Surrounding the middle cylinder 6 and 75 in sliding engagement with the outer downwardly extending annular edge portion of cup leather 7, is the relatively movable cylinder 15 secured at its upper end to head 16, which is fixedly connected with stem 80 11 and handle 12, as shown. Head 16 is provided with an air inlet check valve 17 of well known construction, providing for inflow of air on upward movement and sealing against outflow on downward movement, so as to trap the air in the interior 85 of chamber 18 of cylinder 15, between head 16 and cup leather 7.

Cylinder 15 extends downwardly beyond cup leather 7, as shown, co-extensive with 90 the length of rod 11, and provides between its closed lower terminal and the cup leather 7, and between its wall and inner cylinder 6, a compression chamber 19.

Cylinder 15 is provided at its lower end, 95 substantially on the same horizontal plane with cup leather 13, with a terminal closing cup leather 20. The latter is turned upwardly by its inner flange portion around the exterior of cylinder 6, so as to entrap 100 air in chamber 19 on upward movement and to admit air into chamber 19 upon downward movement. The outer portion of cup leather 20 is turned downwardly within and bears against the interior surface of the outermost stationary cylinder 21 which, like cylinder 6, is fixedly connected with and mounted in the base 2, concentric with cylinders 15 and 6.

The upper portion of cylinder 21 is provided with a terminal cap 22, the upper portion of which makes a close sliding fit 110

with the exterior of cylinder 15, as it moves upwardly or downwardly, and a series of air inlet ports 23 open into an annular chamber 24 intervening between said cylinders.

5 Cup leather 20 is secured to the lower end of cylinder 15 by an inner cap plate 25 secured upon the cylinder and an outer co-acting plate 26 and connecting screws or bolts 27. Plate 26 is provided with a series 10 of laterally extending thin elastic tongues 28 adapted to be bent downwardly within the exterior annular flange portion 29 of cup leather 20 and to press the same outwardly at all times against the inner wall 15 of cylinder 21. Tongues 28 are, however, sufficiently light to permit of receding movement of the cup leather flange 29 on upward movement of cylinder 15, so as to provide for the passage of air from chamber 24 to 20 the enlarged area of chamber 30 intervening between stationary cylinders 6 and 21, below the movable cup leather, and above base 2. The outer flange of cup leather 7 and cup leather 13, as well as cup leather 29, are 25 similarly pressed outwardly by the tongues 28 of a similar ring plate or washer 26, secured in the manner shown.

At its upper portion, preferably immediately below the attaching ring 9 of cup leather 7, cylinder 6 is provided with a series 30 of transverse air inlet ports 31 opening into interior chamber 32 between the inner stationary cylinder 6 and the central movable plunger rod 11.

35 By this construction, I provide for an inflow of air into chamber 18 through check valve 17 upon upward movement of the stem 11 and cylinder 15 by handle 12, and on downward movement into concentric 40 chamber 24 through air inlet ports 23, which ports admit air alternately with the admission of air through check valve 17, said check valve being closed on downward movement.

45 The operation throughout is as follows. Assuming the plunger raised to its upper limit of movement, on downward movement any air in chamber 4 will be ejected through port 3, and any air in chamber 30 will pass 50 upwardly within the inner flanges of cup leather 20 into chamber 19. At the same time, atmospheric air will pass through ports 23 downwardly into chamber 24, until the plunger rod and cylinder 15 are lowered to 55 the bottom position. Upon upward movement, air in chamber 24, due to the partial vacuum created in chamber 30, will pass downwardly thereinto around the outer flange 29 of cup leather 20, and at the same 60 time atmospheric air will flow inwardly through check valve 17 to chamber 18, thereby filling both chambers 30 and 18. At the same time, any air in chamber 19 will, on upward movement, be forced under compression through ports 31 into chamber 32, 65

and, due to the partial vacuum created in chamber 4, will pass downwardly thereinto around cup leather 13, and become trapped in chamber 4.

The same operation will be repeated upon 70 each downward and upward movement, admitting fresh air at each movement, through check valve 17 and ports 23 alternately, which is successively and cumulatively compressed, the final highest compression occurring in chamber 4 of the smallest cross area, and with the greatest resulting compressing power and action, by the central cup leather 13.

It will be understood that ports 23, 31, 80 and check valve 17 may be varied in number or size, so that the sizes and proportions of the several ports or other details of construction may be changed or varied by the skilled mechanic, but that all such changes 85 are to be considered as within the scope of the following claims.

What I claim is:

1. A triple cylinder air pump comprising a base, an innermost high pressure cylinder 90 secured in the base and provided with an air inlet and an outlet delivery port, an outermost cylinder also mounted in the base provided with an air inlet port, a reciprocable cylinder intervening between said cylinders provided with an air inlet port, and a co-acting central plunger within the innermost cylinder.

2. A triple cylinder air pump comprising a base, an innermost high pressure cylinder 100 secured in the base and provided with an air inlet and an outlet delivery port, an outermost cylinder also mounted in the base provided with an air inlet port, a reciprocable cylinder intervening between said cylinders provided with an air inlet port, a co-acting central plunger within the innermost cylinder, and means providing packed sliding engagement between said several parts.

3. A triple cylinder air pump comprising a base, an innermost high pressure cylinder secured in the base and provided with an air inlet and an outlet delivery port, an outermost cylinder also mounted in the base 115 provided with an air inlet port, a reciprocable cylinder intervening between said cylinders provided with an air inlet port, a co-acting central plunger within the innermost cylinder, and means providing packed sliding engagement between said several parts in one direction of movement and adapted to provide intervening air circulation in the other direction.

4. A triple cylinder air pump comprising a base, an innermost high pressure cylinder secured in the base in circulating communication with a supply conduit and provided at its top with a terminal packing cup and an adjacent air inlet port, an outermost cyl- 125 130

inder mounted in the base having a terminal air inlet port, an intervening reciprocable cylinder having at its inner end a packing cup engaging said cylinders, and a central 5 plunger fixedly connected with the reciprocable cylinder having at its inner end a packing cup engaging the innermost cylinder.

5. In combination, a base provided with 10 an outlet conduit, a central high pressure cylinder secured to the base in communication with said conduit and having at its upper end a packing cup and an air inlet port, an outer cylinder secured to the base 15 having an air inlet port at its uppermost end, a central plunger extending through said packing cup provided with a terminal packing cup and an outer handle, and a cylinder fixedly connected therewith having an 20 air inlet valve and extending inwardly between the central and outer cylinder and provided with a terminal packing cup engaging said cylinders.

6. In combination, a base provided with 25 an outlet conduit, a central high pressure

cylinder secured to the base in communication with said conduit and having at its upper end a packing cup and an air inlet port, an outer cylinder secured to the base 30 having an uppermost air inlet port, a central plunger extending through said packing cup provided with a terminal packing cup and an outer handle, and a cylinder fixedly connected therewith having an air 35 inlet valve and extending inwardly between the central and outer cylinder and provided with a terminal packing cup engaging said cylinders having means for laterally extending its outer portion.

7. The combination with a reciprocable 40 member, of a packing cup thereon having an outer annular flange and an inner reversed flange, a holding ring provided with laterally extending spring tongues engaging the outer annular flange, and means for 45 holding said parts in position.

In testimony whereof I hereunto affix my signature.

CHARLES S. McCLELLAND.
